P. B. WESSON

SAFETY FAUCET

Filed Sept. 29, 1921

FIG. 1.

FIG. 2.

Paul B. Wesson,

INVENTOR.

BY

Frank A. Cutler,

ATTORNEY.

UNITED STATES PATENT OFFICE.

PAUL B. WESSON, OF SPRINGFIELD, MASSACHUSETTS, ASSIGNOR TO HAMPTON BRASS COMPANY, OF SPRINGFIELD, MASSACHUSETTS, A CORPORATION OF MASSACHUSETTS.

SAFETY FAUCET.

Application filed September 29, 1921. Serial No. 504,078.

To all whom it may concern:

Be it known that I, PAUL B. WESSON, a citizen of the United States of America, and a resident of Springfield, in the county of 5 Hampden and State of Massachusetts, have invented a new and useful Safety Faucet, of which the following is a specification.

My invention relates to improvements in safety or relief faucets or cocks, it being understood that the term faucet as herein used includes cocks, and said invention comprises a spring-pressed valve for an inverted valve-seat, a screw provided with the usual stem and handle, and a plunger interposed between said screw and said valve, together with such other parts and members as may be necessary or desirable in order to render the faucet complete and serviceable in every particular, all as hereinafter set forth.

20 This faucet is adapted to be used in the ordinary manner for the discharge of water from a hot-water boiler or tank, but is provided with automatic means whereby relief is afforded in the event the pressure in such 25 tank becomes excessive.

The primary object of my invention is to provide a relief or safety faucet for use in connection with a hot-water boiler or tank, which faucet is comparatively simple and 30 inexpensive in construction, and can be operated manually in the customary manner for the purpose of drawing water from the tank, yet is capable at all times of being opened automatically, under an excessive or 35 at a predetermined pressure, to permit the water to flow through and escape and thus prevent explosion of or injury to said tank.

Another object is to produce a faucet of this character which comprises but few 40 parts, and is free from liability of sticking, clogging, or otherwise getting out of order.

A further object is to incorporate this safety feature in a faucet without materially increasing the size of the faucet or 45 changing the general shape and character of the same.

Only one valve is employed, and such valve is of the construction of valves most commonly used in faucets generally, so that 50 the same can be repacked at any time and the normal efficiency of the same thereby maintained.

Other objects and advantages will appear

in the course of the following description.

I attain the objects and secure the advantages of my invention by the means illustrated in the accompanying drawings, in which—

Figure 1 is a side elevation of a faucet which embodies a practical form of my invention, the casing and the other inclosing members being broken away or in section so as clearly to show the parts within, and, Fig. 2, a top plan of the valve.

Similar reference characters designate similar parts throughout the several views.

In Fig. 1, I show a casing 1 which superficially has the appearance of an ordinary faucet casing, but which differs from the latter in a number of important particulars, as will presently appear. The casing 1 has therein the usual inlet chamber 2 and outlet chamber 3, and is provided on top with the customary barrel 4. In the barrel 4 is a chamber 5, and in the lower part of the casing 1 is an intermediate chamber 6. The inlet chamber 2 communicates with the intermediate chamber 6 through an opening in a partition surrounded by an inverted valve-seat 7, and said intermediate chamber communicates with the outlet chamber 3 through an opening 8 below a vertical wall 9 of said partition that separates said outlet chamber from said inlet chamber above said valve-seat. A part that forms a guide 10 depends from the floor of the chamber 5 and extends downwardly into the opening surrounded by the valve-seat 7, that portion of said guide which extends into said opening being of less diameter than that of the seat. The guide 10 ends at the bottom on a horizontal plane that is above the horizontal plane of the valve-seat 7, and said guide has a central passage through the same to receive a vertical plunger 11.

The wall of the chamber 5 is internally screw-threaded at 12, and a screw 13 is in engagement with the threaded portion of said wall. When the parts are assembled the base of the screw 13 is adapted to engage the top of the plunger 11, a portion of said screw being broken away in Fig. 1 to show such engagement more clearly.

A stem 14 rises from the top of the screw 13, and a handle 15 is mounted on the upper terminal of said stem. A screw-cap 16 en-

circles the stem 14, and is adapted to be screwed onto the upper terminal of the barrel 4 to close the top of said barrel. Within the screw-cap 16 is a packing member 17 and a packing-ring 18 which prevent the escape from the top of the chamber 5 of any water that may find its way into said chamber 5. The packing-ring 18 rests on the upper edge of the barrel 4, and the screw-cap 16 has a shoulder that bears on said ring when said cap is screwed down into place. The packing member 17 fits the space around the stem 14 between the packing-ring 18 and the portion of the screw cap 16 that is above said ring, and the latter encircles said stem. The parts and members above the screw 13, which have just been described, are old and well-known.

20 Inasmuch as a downward movement of the screw 13 is required to open this faucet, instead of an upward movement, as will presently be made plain, I prefer to provide said screw with left-hand instead of right-hand threads, making the threads 12 in the barrel 4 to correspond, of course, so that the directions of movement to which one is accustomed in opening and closing valves will be the same in this as in the ordinary type 30 of valves.

The chamber 6 is cylindrical, and a valve 19 for the valve-seat 7 is located in said chamber and adapted to be moved up and down therein. The valve 19 has a sliding fit in the chamber 6. Said valve is of usual construction and includes a packing 20 held in place by a screw 21. The packing 20 can be removed, after taking out the screw 21, and a new packing substituted for the old, 40 the new packing being secured in the valve 19 by means of said screw when the latter is screwed back into place. The head of the screw 21 is of a size which permits the same to enter the bore provided in the guide 45 member 10 for the plunger 11, and the base of said plunger is received on said head. The bottom of the guide 10 is a sufficient distance above the horizontal plane of the valve-seat 7 to avoid interfering with the 50 complete seating of the valve.

A screw cap 22 is provided for the bottom of the chamber 6 and completes the same, said cap being in screw-threaded engagement with the wall of said chamber and forming a tight joint therewith. The valve 19 has a stem 23 that extends downwardly through the chamber 6 into a vertical recess 24 in the screw-cap 22. A spiral-spring 25 encircles the valve-stem 23 between the 55 valve 20 and the bottom of the chamber 6 formed by a portion of the screw-cap 22, and normally retains said valve in closed position.

60 It will have been observed that the axes of the stem screw 13 and its stem 14, the

plunger 11, the valve 19, and its stem 23, and the recess 24 are all in the same straight line.

The valve 19 and the spiral-spring 25 are placed in position while the screw-cap 22 is disconnected, and then said cap is screwed into place on the bottom of the wall of the chamber 6, to close and complete said chamber, receive the lower portion of and center the stem 23, and provide a support on the lower terminal of said spring. When desired for any reason to obtain access to the chamber 6, the screw-cap 22 is removed, and with it the valve 19. This will be done when the valve needs repacking. Access 70 may be had to the chamber 5 by removing the screw-cap 16 and the screw 13. It will be necessary to remove the screw-cap 16 only in the event the packing within said cap needs replacing.

80 The plunger 11 can be placed in position either from above before the screw 13 is introduced into the barrel 4, or from below before the valve 19 is inserted in the chamber 6, or ahead of said valve while the same is being inserted. In the event the plunger 11 drops down with the valve at the time said valve is removed from the chamber 6, said plunger is inserted in the guide 10 again ahead of said valve when the latter is 85 replaced.

90 Normally the spiral-spring 25 retains the valve 19 in tight contact or engagement with the valve-seat 7, so that no water from the chamber 2 can escape through said valve-seat. The valve 19 is opened manually by grasping the handle 15 and turning the stem 14 and the screw 13 in the direction to cause said screw to travel downwardly in the chamber 5. The screw 13 carries downwardly with it the plunger 11, and the latter bearing as it does on the valve screw 21 forces the valve 19 downwardly and away from the valve-seat 7, against the resiliency 100 of the spiral-spring 25, and so opens said valve-seat and permits the water to pass from the chamber 2 through said seat into the chamber 6. From the chamber 6 the water passes through the opening 8 into the chamber 3, and out through the open mouth thereof. The valve 19 is closed manually by rotating the operating parts in the opposite direction, and thus permitting the spiral-spring 25 to raise said valve and force the 105 same into close contact with the valve-seat 7. Further flow of water from the chamber 2 is now cut off. To all intents and purposes, therefore, the operation of the valve by hand is substantially the same in this faucet as in faucets of ordinary construction.

110 Sufficient upward movement of the screw 13, before it contacts with the packing-ring 18, must be permitted to free the valve 19 entirely from the restraining force of said screw, so that the spiral-spring 25 can actu-

ate said valve into its closed position freely and fully, and this even after the packing 20 has become worn.

Assuming that, while the valve 19 is closed, the pressure of the hot water in the chamber 2 becomes greater than the spiral-spring 25 is able to resist, said spring yields under such pressure exerted on the valve 19, and permits said valve to be forced down- 10 wardly away from the valve-seat 7, when the water escapes from the chamber 2 through said seat into the chamber 6, and from the latter through the opening 8 into the chamber 3, in the same manner as when said valve 15 is opened by hand. As soon as the pressure in the chamber 2 is reduced to a point which is less than the force of the spiral-spring 25, said spring acts to raise the valve 19 again and cause the same to close the valve-seat 7, 20 when the faucet resumes its functioning or is ready to function under normal conditions.

In the foregoing it is seen that a single valve in this faucet serves both as a general- 25 purpose valve and a relief valve.

Since the valve 19 and its stem 23 are guided in the manner hereinbefore explained, no difficulty is experienced by the spiral-spring 25 in properly and completely 30 seating or closing said valve and retaining the same in closed position, in the absence of pressure from above which forces said valve from its seat, or upon the removal of such pressure.

More or less change may be made in the 35 shape, size, construction, and arrangement of some or all of the parts of this faucet without departing from the spirit of my invention or exceeding the scope of what is 40 claimed.

What I claim as my invention, and desire to secure by Letters Patent, is—

1. The combination, in a safety faucet, with a casing having therein inlet and outlet chambers and an intermediate chamber 45 opening into said outlet chamber, and provided with a valve-seat between said inlet chamber and said intermediate chamber, and with a guide which has a passage through the same that is in line with the axis of said valve-seat, of a spring-pressed valve for said seat, a screw arranged and adapted to be rotated and reciprocated in said casing, and a plunger operating in said guide between said valve and said screw. 50

2. The combination, in a safety faucet, with a casing having therein inlet and outlet chambers and an intermediate chamber, and provided with an inverted valve-seat between said inlet and intermediate chambers, 60 said intermediate chamber opening below said valve-seat into said outlet chamber, and further provided with a guide having a passage therethrough which is in line with the axis of said valve-seat, and a cap forming the bottom of said intermediate chamber, said cap having a recess therein which is also in line with the aforesaid axis, of a valve in said intermediate chamber for said valve-seat, said valve having a stem which 65 is received in said recess, a spring between said cap and said valve, a screw arranged and adapted to be rotated and reciprocated in said casing, and a plunger in said passage between said valve and said screw. 70
